Att'y.

UNITED STATES PATENT OFFICE

HARRY G. NORWOOD, OF NEW YORK, N. Y., ASSIGNOR TO THEODORE F. VON DORN, OF NEW YORK, N. Y.

SPRING NUT LOCKING DEVICE FOR RAIL JOINTS

Application filed September 20, 1929. Serial No. 394,064.

This invention pertains to a new and novel spring nut locking device, and has been especially designed for use in connection with railway rail joints.

5 The main object of the invention is to provide simple, strong, durable, economical, practical and efficient means whereby the meeting ends of the rails will be safely locked and maintained in proper alignment.

10 Further objects of the invention are to so construct an effective locking device from a single piece of high grade spring steel of the desired dimensions that it will securely maintain the locking nuts in locked condition; 15 that it will bind against the securing bolts and retain said bolts in proper transverse alignment, and will serve to prevent any lateral swerving or movement of the meeting ends of the track rails with which it is 20 connected.

The foregoing and such other objects as may appear from the ensuing description are attained by the construction, location, arrangement, combination and formation of 25 the several parts hereinafter more fully described, illustrated in the accompanying drawings and more particularly pointed out in the claims appended hereto, it being understood that slight changes in the precise 30 shape, proportions and minor details of construction may be resorted to without departing from the spirit or sacrificing any of the advantages of the invention.

In the accompanying drawings forming a 35 part of this specification it will be seen that:

Figure 1 is a side elevation of the improved means embodying my invention shown in connection with a railway rail joint.

Figure 2 is a plan view showing a metallic 40 bar from which the locking device is formed, showing the bar broken away at each end portion thereof.

Figure 3 is an enlarged perspective showing the locking device disconnected from the 45 rail joint.

Figure 4 is an inverted enlarged perspective of the device shown in Fig. 3, and

Figure 5 is a top plan thereof.

In the embodiment of my invention as illustrated, it will be seen that the numeral 1

designates the railway track rails, 2 the rail clamping splice bars, each of said bars being provided with openings therethrough for the reception of a suitable number of securing bolts 3, each bolt being passed through the track rail and the opening formed through the splice bars and securely fitted to the threaded end portion of each bolt is a securing nut 4, said nuts being preferably fitted so as to alternate on opposite sides of the rail joint.

It will be perceived that this invention provides an improved, novel and peculiarly formed locking device formed from a single piece of metal, and preferably made from a 65 heat treated high grade of spring steel such as is usually employed for like purposes, said locking device being stamped or punched out from a bar of metal 5, in a substantially H-shaped formation, thereby reducing the 70 waste of metal to the minimum amount, and so formed as to overlap the meeting ends of the track rails, and is firmly and tightly secured under high spring tension against the outer face of each of the clamping splice 75 bars 2 by the securing bolts and nuts disposed nearest the meeting ends of the track rails, each locking device being stamped or forged by the medium of suitable dies from a single piece of metal folded upon itself at its 80 central portion 6 and formed with a central vertical depression 7 at each side thereof; outwardly extended shouldered portions 8, and longitudinal extensions 9, which extend from the shouldered portions 8 to each of its 85 outer ends, and a bolt opening 10 formed therethrough near each of its end portions, as clearly shown in Figs. 3 and 4.

It will be clearly obvious from this particular formation of the locking device that when it shall have been firmly secured in contact with the rail clamping splice bar 2, by the proper adjustment and tightening of the securing nuts fitted to the bolts, each 90 section of the locking device at the right and left of its vertical center will be under intense spring tension against the inner face of the nut thus forcing the nut under extreme 95 pressure into contact with the threaded por- 100

- tion of the bolt, and at the same time will bind tightly against each bolt, hence when each nut shall have been completely adjusted all accidental turning or loosening of the nuts, usually caused by the excessive jarring that emanates from the rolling stock passing over the joints, will be prevented, and the bolts will be maintained in their proper transverse alinement.
- 10 It will also be evident that in the event that a splice bar should be accidentally broken, this type of locking device possessing unusual strength will readily serve to retain the rails in proper alinement until the 15 break is discovered and repaired, thereby preventing what is known as "lipping" of the track rails which is liable to cause a derailment of the rolling stock.

It will be understood that any required or 20 desired number of holes may be formed through the end portions of the track rails and through the splice bars, and that any suitable number of bolts and securing nuts may be employed in the proper locking and 25 securing of the track rail joints.

Having thus described my invention, what I claim and desire to secure by Letters Patent is:

30 1. A spring nut locking device for rail joints comprising a single piece of spring steel folded upon itself at its central portion, a vertical depression formed at each face of its central portion, a longitudinal portion extending from each side of its central portion to each outer end thereof, and an opening formed at each end portion for the reception of a securing bolt.

40 2. A spring nut locking device formed from a single H-shaped piece of metal, said H-shaped piece being centrally recessed across its outer and inner face and folded upon itself at said recessed central portion, and a longitudinal portion extending from each side of its central portion to each outer 45 end thereof, said device being adapted for the reception of a securing bolt at each oppositely disposed end portion.

50 3. A spring nut locking device for rail joints, comprising an H-shaped piece of spring steel folded upon itself centrally, a central vertical depressed portion at each face thereof, an outwardly extended shouldered portion formed at each end of the depressed portions, a longitudinal portion extending from each shouldered portion to its outer end, and an opening formed at each end portion for the reception of a securing bolt.

60 4. A spring nut locking device of the character described, comprising a single piece of spring steel folded upon itself centrally, a centrally disposed vertical depression formed at each face thereof, a shouldered portion extending outwardly from each end of each depression, and a longitudinal portion ex-

tending from each shouldered portion to its outer end, said longitudinal portions each being formed with a bolt opening therethrough near its outer end.
